(57) CLAIM

The ornamental design for a pillow as shown and described.

DESCRIPTION

FIG. 1 is a top perspective view of a pillow, showing my new design;

FIG. 2 is a bottom perspective view thereof;

FIG. 3 is a front elevational view thereof;

FIG. 4 is a rear elevational view thereof;

FIG. 5 is a left side view thereof, the right side view being a mirror image of FIG. 5;

FIG. 6 is a top plan view thereof;

FIG. 7 is a bottom plan view thereof;

FIG. 8 is a cross-sectional view taken through line 8-8 of FIG. 3 thereof; and,

FIG. 9 is a cross-sectional view taken through line 9-9 of FIG. 6 thereof.

The broken lines in the figures are for the purposes of illustrating portions of the pillow, which form no part of the claimed design. Additional broken lines indicate section cut locations and form no part of the claim.
